UNITED STATES PATENT OFFICE.

WILLIAM L. OGDEN, OF BURLINGAME, KANSAS.

GAITING ATTACHMENT FOR SULKIES OR OTHER VEHICLES.

No. 874,617.

Specification of Letters Patent.

Patented Dec. 24, 1907.

Application filed April 13, 1907. Serial No. 367,925.

To all whom it may concern:

Be it known that I, WILLIAM L. OGDEN, a citizen of the United States, residing at Burlingame, in the county of Osage and State 5 of Kansas, have invented a new and useful Improvement in Gaiting Attachments, of which the following is a specification.

The invention relates to gaiting attachments for sulkies and other vehicles, especially in the training of horses, and more especially in the training and gaiting of colts.

The object of the invention is to improve generally upon gaiting attachments, and to provide a gaiting attachment by the use 15 and adjustment of which the colt can be prevented from striking or interfering with his feet, that is, from striking his front foot with his hind foot. This has heretofore been remedied in the shoeing; and I am 20 aware of a gaiting pole having been used.

My invention consists of two such poles, one on each side of the horse, with a cross-bar to which the rear ends of the poles are adjustably secured, the cross-bar itself being adjustably secured to the cross-bar, or 25 swing-tree, of the vehicle, or to any other suitable part of the vehicle.

It further consists of the improvements and combinations hereinafter pointed out 30 and claimed.

In the drawings accompanying and forming part of this specification, Figure 1 represents the shafts and forward portion of a vehicle or the upper part of a sulky, with 35 my improvement attached thereto. Fig. 2 is a view of one of the side poles. Fig. 3 is a similar view showing the slots. Fig. 4 is a view of the cross-bar.

Similar reference numerals indicate like 40 or corresponding parts in the several views.

5, 5 represent a pair of shafts of a sulky or other vehicle, and 6 may represent the sulky seat.

7 is the cross-bar of the shafts, and 8 is 45 the swing-tree pivoted thereon in the usual manner.

9 is the cross-bar of my attachment, and 50 10, 10 are the side poles, the forward ends of which may be secured to the shafts, as by the straps 11, 11, and the rear ends of which are secured to the attachment cross-bar 9, as by the straps 12, 12. The cross-bar 9 may be attached to the sulky by means of a strap 13. The several straps 55 may pass through the slots 14, 14, and for

each strap at each connecting point there may be a series of slots so as to make the attachment variously adjustable. I prefer to use the ordinary straps for the various connections just described, as they 60 serve best to withstand the strains to which the devices are subjected and as they are most readily to be attached or detached and also as they serve best for the several 65 adjustments desired in my attachment.

Now, in the use of my attachment, I prefer to adjust the side poles on the cross-bar 9 just far enough apart to make room for the hind quarters of the colt between the side poles. If, now, it is found that the colt 70 strikes when moving exactly straight ahead, the attachment may be shifted slightly to the right or left, by means of the strap 13, thus throwing the hind quarters of the colt to a position in which he does not strike. On 75 the other hand it frequently occurs that a horse may travel slightly to one side and strike; and in such case the attachment may be used to set him in a straight line, or in any other position in which he will not interfere. 80 The difficulty with the use of a single pole is that though the horse may be kept from one side, he is not prevented from going to the other side. With my device, however, I contemplate that the position of the horse in 85 traveling shall be absolutely regulated and controlled, not allowing him to swerve in either direction from that position in which it is found he travels best. It is also contemplated that with my attachment, the 90 driver or trainer shall try the attachment in various positions until he shall get the exact position in which he finds the horse to work best. And I find that with a few lessons in 95 that position, a horse will not only find comfort in traveling, but will retain that position. As heretofore stated, it is customary to try to remedy striking in the shoeing; but I find that it can be remedied absolutely by the use of my gaiting attachment, on the 100 new principles herein explained. I am also aware of the gaiting pole, heretofore used.

What I claim is:

1. A gaiting attachment comprising two side poles, the forward ends being attachable 105 to the respective shafts and the ends being attached to the attachment cross-bar, a cross-bar adjustably secured to the forward portion of the vehicle, so that said attachment may be used to throw the rear portion of the 110

horse to one side or the other and to prevent him from swerving to either side of his intended position.

2. A gaiting attachment comprising two side poles and a cross-bar, the forward ends of the poles being attachable to the vehicle shafts, and the rear ends being attached to the ends of the cross-bar and being laterally adjustable thereon, the cross-bar being adjustably attachable to the forward portion of a vehicle.

3. A gaiting attachment comprising two side poles and a cross-pole, the forward ends of the side poles being attachable to the respective shafts of a vehicle, and their rear ends being laterally adjustably attachable to the cross-pole, and said cross-pole being adjustably attachable to a cross-bar of the vehicle, so as to control the position of the horse in traveling and prevent him from swerving in either direction.

4. A gaiting attachment for vehicles having shafts, comprising two side poles and a cross-pole, straps for attaching the forward ends of the side poles to the shafts of the vehicle, straps for adjustably fastening the side poles to the cross-pole, and a strap for ad-

justably securing the cross-pole of the attachment to the cross-bar of the vehicle; whereby the attachment is adjustable to horses having hind-quarters of different widths and whereby said attachment may be shifted from side to side so as to positively control his position in traveling; substantially as set forth.

5. A gaiting attachment for vehicles having a pair of shafts, comprising the combination of two side poles and a cross-pole, straps for attaching the ends of the side poles to the shafts, straps for adjustably fastening the rear ends of the side poles to the ends of the cross-pole, and a means for securing the cross-pole to the cross-bar of the vehicle so that said cross-pole shall be laterally adjustable so that thereby the hind-quarters of the horse may be thrown to either side and confined in any desired position within the shafts; substantially as set forth.

In testimony whereof I have hereunto set my hand in the presence of witnesses.

WILLIAM L. OGDEN.
